CLAIM

The ornamental design for a portable bidet, as shown and described.

DESCRIPTION

FIG. 1 is a first perspective view of a portable bidet showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is a perspective view of a portable bidet according to a second embodiment.

The broken lines immediately adjacent the claimed surfaces depict the bounds of the claimed design, whereas the remaining broken lines depict portions of the portable bidet, all of which form no part of the claimed design.

1 Claim, 9 Drawing Sheets
